UNITED STATES PATENT OFFICE

105,582

DESIGN FOR A COMBINATION DESK UNIT

Dillman C. Houston, Los Angeles, Calif.

Application April 20, 1937, Serial No. 68,878

Term of patent 7 years

To all whom it may concern:

Be it known that I, Dillman C. Houston, a citizen of the United States of America, residing at Los Angeles, in the county of Los Angeles and State of California, have invented a new, original, and ornamental Design for a Combination Desk Unit, of which the following is a specification, reference being had to the accompanying drawing, forming part thereof.

In said drawing,

Figure 1 is a plan view of a combination desk unit showing my new design;

Figure 2 is a view of the same in side elevation; and

Figure 3 is a front end view thereof.

I claim:

The ornamental design for a combination desk unit as shown.

DILLMAN C. HOUSTON.
